United States Patent Office

Des. 205,318
Patented July 19, 1966

205,318

CONTAINER FOR PAINTS OR THE LIKE

Harry Meth, Cincinnati, Ohio, assignor to Rainbow Crafts, Inc., Cincinnati, Ohio, a corporation of Ohio

Filed Sept. 28, 1964, Ser. No. 81,901

Term of patent 14 years

(Cl. D58—17)

FIG-1

I claim:

The ornamental design for a container for paints or the like, as shown.
